GLOW DISCHARGE DEVICE

Gerald G. Carne, Rockaway, N. J., assignor to
 Radio Corporation of America, a corporation of
 Delaware

Application August 19, 1948, Serial No. 45,173

3 Claims. (Cl. 250—27.5)

1

The present invention relates to a glow discharge device sometimes characterized as the type of a "trigger tube." It is comprised essentially of an anode, "trigger" grid or anode and a cathode and is used primarily for controlling circuits requiring monitoring.

Tubes of this type are used ordinarily with a photo-cell and employ a cold cathode, anode grid and an anode so that when excited a glow discharge takes place between the anode and the cathode. The anode grid is primarily an auxiliary or control electrode between the anode and the cathode. The anode grid is relatively closely spaced to the cathode and is responsive to a "transfer current." By the use of this term it is meant the value of the current required to pass between the cathode and the trigger or grid anode before conduction can take place to the anode, this transfer current, being a function of the electric field intensity at the surface of the cathode, varies with different cathode shapes.

It is an object of the present invention to provide a trigger type tube having a cathode, the curvature of which is drawn with the anode at the center of the radius of curvature. This arrangement makes it possible to greatly reduce the transfer current between the cathode and the anode grid.

Another object is the provision of an electrode construction that has the curvature of the cathode designed to give maximum tube operating efficiency so that the electrode assembly may be incorporated in a miniature construction.

Another object of the invention is the provision of an anode grid between the cathode and anode concentric with and having a curvature conforming substantially to the curvature of the cathode. This gives a greater functional area to the trigger anode close to the cathode, thus preventing excessive deterioration of the cathode surface adjacent the curvature of the trigger anode.

Other objects having to do with features of construction and arrangement of parts will manifest themselves as the description proceeds.

The accompanying drawing illustrates a form of a tube embodying the invention in which:

Figure 1 is a central, longitudinal fragmentary view, partly in elevation, of a glow discharge device of one embodiment of the invention; and

Figure 2 is a cross section, on the line 2—2 of Figure 1, illustrating the arrangement of the electrode assembly.

Referring to the drawing, the present discharge device comprises an envelope 1 having a header 2

provided with fillets 3 for accommodation of conductors 4. The envelope is filled with a rare gas such as argon or neon, or mixtures of such gases, at a pressure of the order of from 5 to 100 millimeters of mercury.

An effectively large elongated cold type cathode 5 is supported from the lead wires 4 on an insulating member 16 by means of tabs which extend through the insulating member, and may be of any suitable material such as nickel coated on its inner surface 6 with an emission material, such as barium or strontium carbonates. The outer surface 7 of the cathode is preferably coated with aluminum oxide to prevent a discharge from occurring at the back side of the cathode as is customarily done in this form of tube.

The anode 13 consists of a carbon rod partly enclosed in a hollow glass "pant leg" 10 cemented to the stem or header 2 of the tube and extending up through insulating member 16. The lead 11 is surrounded by the rod 10 of the anode. Carbon is used for the anode proper because it has very poor electron emission and thus tends to avoid a breakdown during the negative half cycle of alternating voltage which is universally used in the operation of my tube. That is to say, the tube is intended to function or breakdown on the positive half of the cycle only, but due to copious emission which frequently occurs with certain types of anode materials, the breakdown occurs with the negative side or cycle which is detrimental to proper circuit control operations.

A wire trigger or anode grid 12 has depending legs 12a which extend down through accurately located holes in insulating member 16 and are connected to leads 15. Above insulating member 16 and resting on the same, the anode grid extends radially toward the cathode so that the upper arcuate portion of the anode grid which is concentric with the cathode is closely spaced with respect thereto as shown in Figure 2 and therefore has substantially the same curvature as the cathode. The cathode and anode grid are readily formed accurately dimensioned according to well known practices. However, to attain the accurate positioning of the two required for the proper functioning of the device, I accurately locate the holes provided in insulating member 16 for the cathode lugs and legs 12a.

It should be pointed out that there is a critical radius of curvature in the formation of the cathode and the anode grid. If they are made of too large radii, they require excessive field intensity which produces a disproportionate trans-

fer current with a consequent deleterious effect upon the operation of the tube. The same objection is substantially true if they are made of too small radii. This follows from the fact that the transfer current, being a function of the electric field intensity at the surface of the cathode, varies with different cathode shapes. Consequently, if the curvature of the cathode is increased so as to approach a plane, which would be the case if a large center of the radius of curvature was used, there is an increase in the transfer current required; vice versa, if the center of the radius of curvature of the cathode was made less than such reduction, there would also be an increase in the transfer current. For example, where the center of the radius of curvature of the cathode was materially reduced from an optimum, as was the case where the center of the cathode was on a circle with the anode, there would also be an increase in the transfer current.

I have discovered best results are obtained when the anode is positioned at the center of the radius of curvature of the cathode and the trigger grid.

The spacing between the cathode and the anode grid will vary for different types of tubes. It will also be appreciated that with a reduction in the size of the tube, there will be an inherent variation in its operation. However, these are matters of technique which can be easily determined by those skilled in the art from the foregoing description.

While I have set forth a preferred embodiment of the invention and described it in detail with respect to said embodiment, I do not wish to be limited to the exact construction set forth but desire to claim all modifications thereof that come within the scope of the appended claims.

What I claim as new is:

1. A glow discharge device comprising an

elongated arcuate cathode, a wire anode grid, and a rod-shaped anode, said anode grid having an arcuate portion concentric with and conforming substantially to the curvature of the cathode, said anode being coaxial and concentric with said cathode and anode grid, said anode grid being mounted intermediate the ends of said cathode and adjacent one end thereof and between the cathode and anode.

10 2. A glow discharge device comprising an elongated arcuate cathode forming less than half of a cylinder, a rod anode concentric and coaxial with said cathode, and an arcuate wire anode grid concentric and coaxial with said cathode and within the space between said anode and said cathode.

15 3. A glow discharge device comprising an elongated arcuate cathode, a rod shaped anode concentric and coaxial with said cathode, an arcuate wire anode grid concentric and coaxial with said cathode, said anode grid extending transversely of said cathode intermediate the ends thereof spaced from but adjacent one end thereof and between said cathode and said anode, and an 20 insulating member having locating holes formed therein, said cathode having lugs extending through two of said holes, said anode grid having depending legs which extend through two other locating holes and which extend radially 25 toward said cathode on said insulating member.

30 GERALD G. CARNE.
